No. 624,951.

Patented May 16, 1899.

R. LEWIS.

FASTENER FOR BICYCLES.

(Application filed Nov. 16, 1898.)

(No Model.)

FIG. 1.

FIG. 2.

UNITED STATES PATENT OFFICE.

RICHARD LEWIS, OF LLANELLY, ENGLAND.

FASTENER FOR BICYCLES.

SPECIFICATION forming part of Letters Patent No. 624,951, dated May 16, 1899.

Application filed November 16, 1898. Serial No. 696,625. (No model.)

To all whom it may concern:

Be it known that I, RICHARD LEWIS, a subject of the Queen of Great Britain, residing at Llanelli, in the county of Carmarthen, 5 England, have invented certain new and useful Improvements in Locks or Fastening Devices for Bicycles and Similar Vehicles, of which the following is a full and complete specification, such as will enable those skilled 10 in the art to which it appertains to make and use the same.

This invention relates to bicycles and similar vehicles; and the object thereof is to provide an improved lock or fastening device 15 which is adapted to be applied so as to hold a brake in operation to prevent the movement of the wheels of the vehicle.

The invention is fully disclosed in the following specification, of which the accompanying drawings form a part, in which—

Figure 1 is a side view of a lock which I employ for applying the brake; Fig. 2, a similar view, part of the construction being shown in section; Fig. 3, a side elevation of a bolt 25 which forms a part of the lock; Fig. 4, a side view of a key-bolt which I employ; Fig. 5, a side view of a part of the construction shown in Figs. 1 and 2; Fig. 6, a sectional side elevation of a key by which the lock is 30 operated, and Fig. 7 a cross-section on the line 7 7 of Fig. 4.

In the drawings forming part of this specification the separate parts of my improvement are designated by the same letters of 35 reference in each of the views, and in constructing my improved lock for applying the brake I provide a ring or band A, which is adapted to be connected with the handle-bar of the vehicle and which is open at one side 40 and provided with two projecting jaws a, which form a neck through which is drilled a circular hole a², through which is passed the tubular barrel B, screw-threaded at one end, as shown at b, and provided centrally with an 45 annular shoulder b³, adjacent to which, on the screw-threaded end, is formed a cylindrical portion b⁴, which is not screw-threaded. The cylindrical portion b⁴, which is not screw-threaded, is of about the thickness of one of 50 the jaws a, and the other jaw is screw-threaded to correspond with the thread b on the barrel B, and by turning said barrel in one di-

rection said jaws a may be separated, as will be readily understood, the object of this construction being to facilitate the connection 55 of the ring or band A with the handle-bar, it being understood that by turning the barrel B in the other direction the jaws a are drawn together.

The barrel B is closed at one end and provided adjacent thereto and in one side thereof with a transverse opening d, through which is passed a key-bolt D, rectangular in cross-section and provided at its lower end with a head d² and in one side thereof with a notch 60 or recess d³, and mounted in said barrel is a transverse partition-plate H, through which passes a spring-operated bolt E, and on which is wound a spring G, the inner end of which is secured to the bolt E, adjacent to the transverse partition-plate H, as shown at h, and said transverse partition-plate H is provided 65 centrally with an opening, through which the inner end of the bolt E passes.

The open end of the barrel B is closed by a 70 plate C, having a central opening C², and the spring G operates to force the bolt E inwardly and the inner end thereof through the transverse partition-plate H and into the notch or recess d³ in the bolt D. The plate C 75 may be secured to the barrel in any desired manner.

The bolts D and E are shown in detail in 80 Figs. 3 and 4, and in Fig. 6 I have shown a key F, comprising a knob or handle f, having a tubular extension f², the bore of which is screw-threaded, as shown at f³. The outer 85 end of the bolt E is also screw-threaded, as shown at e, and in order to operate the bolt E so as to release the bolt D the key F is inserted through the hole C² in the cap-plate C and connected with the outer screw-threaded 90 end of the bolt E, and said bolt is turned or drawn outwardly, so as to release the bolt D.

The barrel B is provided adjacent to the 95 end with which the cap C is connected with a downwardly-directed shoulder or projection b⁴, to which is secured a strong contractile spiral spring G', which is also secured to the head d² of the bolt D, and in order to operate 100 the brake-lever so as to apply the brake the ring or band A is passed over one end of the handle-bar. The barrel B is then passed through the openings a² and turned so as to

clamp the ring or band securely on the handle-bar. The spring G' is then passed around the brake-lever and the key-bolt D inserted into the opening d, adjacent to the end of the 5 barrel, as shown in Fig. 2, and locked therein by the lock-bolt E, and the spring G' draws up the brake-lever and applies the brake and locks the vehicle.

The end of the bolt D, adjacent to the notch 10 or recess d³, is beveled, as shown at d⁴, and when the bolt D is forced into the barrel B the bolt E is forced outwardly by the beveled portion d⁴ of the bolt D until the said bolt D passes into the barrel, as shown in Fig. 2, 15 after which the bolt E is forced inwardly by the spring G and holds the bolt D in place.

This device is simple in construction and operation and well adapted to accomplish the result for which it is intended and is also comparatively inexpensive.

Having fully described my invention, I claim as new and desire to secure by Letters Patent—

1. The locking device herein described, 25 comprising a ring or band A, open at one side and provided with parallel projecting jaws, a barrel screw-threaded at one end and passed through said jaws, said barrel being closed at one end and open at the other, and provided adjacent to the closed end with a trans- 30 verse opening in one side thereof, a bolt

which is adapted to be inserted into said opening, said bolt being connected with the opposite end of the barrel by a spiral spring, a spring-operated bolt mounted in said barrel and adapted to engage with said first-named bolt, the open end of said barrel being provided with a cap-plate having a central opening, and a key which is adapted to be inserted through said opening and to operate 40 said spring-operated bolt, substantially as shown and described.

2. The herein-described locking device, comprising a clamp open on one side and provided with parallel projecting jaws, a barrel 45 screw-threaded at one end and passed through said jaws, said barrel being provided with a locking-bolt, and a spring-operated bolt adapted to be connected therewith, and said barrel being also provided with a spring one 50 end of which is secured thereto, and the other to the locking-bolt, substantially as shown and described.

In testimony that I claim the foregoing as my invention I have signed my name, in presence of the subscribing witnesses, this 4th day of November, 1898.

RICHARD LEWIS.
